Efficiency

UNITED STATES PATENT OFFICE.

WILLIAM ILE, OF JACKSON, MICHIGAN.

ELECTRIC SWITCH.

Application filed May 26, 1925. Serial No. 33,042.

To all whom it may concern:

Be it known that I, WILLIAM ILE, a citizen of the United States, residing at Jackson, in the county of Jackson and State of Michigan, have invented new and useful Improvements in Electric Switches, of which the following is a specification.

The invention relates to an electric switch of the toggle type.

10 The object of the present invention is to provide a simple, practical and efficient single or double pole switch of the toggle type of strong, durable and comparatively inexpensive construction equipped with means adapted to produce a positive snap motion and capable of maintaining the switch blades firmly in each position of the same.

Another object of the invention is to provide an electric switch of this character 20 of the standard type adapted to be operated with either a lever arm or push buttons.

With these and other objects in view, the invention consists in the construction and novel combination and arrangement of parts 25 hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

35 Figure 1 is a front elevation of an electric switch constructed in accordance with this invention and operated with a lever arm.

Fig. 2 is a side elevation of the same.

Fig. 3 is a vertical sectional view, the 40 switch mechanism being shown in elevation.

Fig. 4 is a central vertical sectional view through the switch mechanism.

Fig. 5 is a front elevation of the switch mechanism.

45 Fig. 6 is a central, horizontal sectional view of the same.

Fig. 7 is a detail view of the operating lever.

Fig. 8 is a detail view of the swinging 50 yoke.

Fig. 9 is a front elevation of the electric switch equipped with push buttons for operating the same.

Fig. 10 is a side elevation of the same.

Fig. 11 is a sectional view through the 55 insulating support, the switch mechanism being shown in elevation.

Fig. 12 is a detail view of one of the push buttons illustrating the manner of connecting the same to the operating lever. 60

Fig. 13 is a sectional view of the same.

Referring particularly to Figs. 1 to 8 inclusive, of the accompanying drawings in which the switch mechanism is operated by a lever arm, 1 designates an insulating block 65 of molded bakelite or other suitable material designed to be mounted in a metallic switch box of the usual type and provided with a compartment 2 for the reception of the switch mechanism. The switch mechanism comprises in its construction a substantially U-shaped supporting bracket 3 composed of spaced sides and connecting bottom portions 4, the sides being approximately triangular and provided with cut 70 away portions or openings 5 and the bottom portions being spaced apart at the said openings and constituting stops for limiting the swing of a pivoted yoke 6 which carries switch blades 7. The bracket is secured by 75 screws or other suitable fastening means within the hollow insulating block and it is provided at the outer faces of its sides with laterally extending pivot studs 8 on which the switch blade carrying yoke is 80 mounted. The yoke 6 is composed of spaced sides and a transverse connecting bottom portion 9 and its sides are enlarged at their upper portions and provided with spaced 85 openings 10 for the reception of rivets 11 or other suitable fastening means for securing the switch blades to one or both of the sides of the swinging yoke.

In the accompanying drawings for convenience of illustration, switch blades are 90 shown secured to one side only of the swinging yoke but it will be readily understood that in practice each of the sides of the yoke may carry switch blades. The sides of the yoke 6 are also provided with 95 bearing recesses 12 open at the bottom to enable the yoke to be hung upon the pivot studs 8 which are formed integral with sides of the supporting bracket. The switch blades 7 which cooperate with front and 100 rear stationary switch contacts 13 and 14

are secured to the swinging yoke by means of a pair of the said fastening devices 11 which pass through the said switch blades and also through inner and outer insulating plates 15 and through an outer face plate 16 constructed of suitable metal and adapted to reinforce and protect the outer insulating plate. Spacing members 17 which are preferably in the form of washers or rings are arranged on the said fastening devices 11 and are interposed between the inner insulating plate and the swinging yoke to offset the switch blades from the side of the yoke and arrange the switch blades in proper position to cooperate with the stationary switch contacts. The stationary switch contacts are arranged to fit between the terminals of the switch blades and are beveled at their rear and front edges respectively, so as to enter readily between the terminals of the switch blades which are slightly spaced as shown for this purpose. The stationary front switch contact 13 consists of a projecting arm formed integral with an approximately L-shaped plate 18 which is secured by screws 19 or other suitable fastening devices to the insulating block in a suitable recess or depression thereof and the said plate 18 is provided at the adjacent side of the switch block with a binding screw 20 and it has a projecting portion 21 to cooperate with the binding screw for enabling an end of a wire to be securely fastened to the binding terminal formed by the side portion of the plate 18 and the binding screw 20. The rear stationary switch contact 14 consists of an approximately L-shaped arm formed integral with an L-shaped plate 22 secured by screws 23 to the insulating block in a recess or depression of the same and provided at the side of the insulating block with a binding screw 24 and constituting a binding terminal. The plate 22 is also provided with projecting portions 25 to cooperate with the binding screw in holding an end of a wire. The stationary switch contacts are shown at one side of the insulating block but may of course, be provided at both sides of the same when the swinging yoke is equipped at both of its sides with switch blades.

The supporting bracket is provided at the apexes of the sides with transversely aligned perforations for the reception of a pivot pin 26 on which is mounted an operating lever 27 composed of a body portion 28 and a plate or member 29 having a shank 30 on which a handle 31 of bakelite or other suitable material is molded. The body portion is approximately U-shaped and is composed of spaced approximately triangular sides and a connecting portion having recesses 32 at its ends to receive lugs 33 of the plate 29. The ends of the plate 29 are reduced and are

bent inwardly at right angles to form the said lugs and the latter are provided with aligned perforations 34 through which passes a pin 35 adapted to perform the double function of securing the two sections or members of the operating lever together and afford means for attaching push buttons to the operating lever when it is desired to operate the switch by means of push buttons as illustrated in Figs. 9 to 13 inclusive. The shank 30 is, of course, omitted when the push buttons are employed. The body portion of the lever is provided at its sides adjacent the plate 29 with ears 36 through which passes the pivot pin 26 and the plate 29 is provided at the pivot pin with a recess to clear the same. The plate and the shank may be conveniently constructed of a single strip of metal doubled centrally to provide a shank of two plies or thicknesses and the plies or thicknesses are then bent outwardly at right angles to the shank to form the plate. The plate may, of course, be formed of a single flat piece of material when the shank is not required. The sides of the U-shaped body portion are provided with open bearing recesses 37 for the reception of laterally extending pivots or trunnions 38 of a rocking plate 39 through which extends a guide bar or member 40 having a head 41 of approximately T-shape with its central arm extending outwardly and arranged in a slot 42 in the transverse connecting portion of the pivoted switch blade carrying yoke. The bar 40 receives a coiled spring 43 which is interposed between the head 41 and the rocking plate 39 and thrusts against the said head and the said plate. The spring throws the swinging yoke to one side or the other as soon as the operating lever carries the spring beyond the dead center and the parts provide a toggle structure and produce a snap motion for positively carrying the switch blades to one position or the other according to the direction in which the lever is operated. The inner end of the bar 40 is split and is spread as shown at 44 after being passed through the rocking plate for securing the spring on the bar 40.

The operating arm or handle 31 extends through a slot 45 in a switch plate or panel 46 which is secured to a wall in the usual manner. The bakelite insulating block is provided at its ends with metal lugs or ears 47 adapted to receive screws or other suitable fastening devices for securing the switch in the said box.

When push buttons 48 are employed as illustrated in Figs. 9 to 13 inclusive of the drawings they extend through openings 49 in a switch plate 50 and they are pivoted by rivets 51 or other suitable fastening devices to ears 52 of collars 53 which are secured on the projecting terminals of the pin 35.

The ends of the pin are headed as illustrated in Fig. 13 of the drawings for retaining the collars 53 on the ends of the pin.

What is claimed is:

5. 1. An electric switch including a support, a switch blade carrying yoke pivoted to the support, a lever composed of an approximately inverted U-shaped lower portion pivoted to the support, an upper portion interlocked with the lower portion and a pin securing the upper portion to the lower portion and having projecting terminals adapted to have push buttons connected with them for enabling the lever to be operated by push buttons, the upper portion of the lever being also adapted to receive a handle for operating the switch, and spring toggle means connecting the lever and the yoke to produce a snap movement of the latter.
- 10 2. An electric switch including a support, a switch blade carrying yoke pivoted to the support, a lever also pivoted to the support and composed of an inverted U-shaped lower portion having terminal recesses at the top, a top portion pivoted on the lower portion and provided with lugs extending into the said recesses for interlocking the upper and lower portions, means for securing the upper and lower portions in their interlocked relation and spring toggle means connecting the lower portion of the lever with the toggle to produce a snap action.
- 15 3. An electric switch including a support, a switch blade carrying yoke pivoted to the support, a lever also pivoted to the support and composed of an inverted U-shaped lower portion having terminal recesses at the top, a top portion pivoted on the lower portion and provided with lugs extending into the said recesses for interlocking the upper and lower portions, a pin arranged beneath the top of the lower portion and passing through the said lugs of the upper portion to secure the two portions of the lever in their interlocked relation, said pin having projecting terminals for the attachment of push buttons, the upper portion of the lever being also adapted to receive a handle for enabling the switch to be operated by the same, and spring toggle means connecting the lower portion of the lever with the yoke.
- 20 4. An electric switch including a support, a switch blade carrying yoke pivoted to the support, a lever composed of an inverted approximately U-shaped lower portion provided at the top with transversely alined ears and having terminal recesses, an upper portion provided with depending lugs fitted in the said recesses, a pin passing through the lugs and arranged beneath the top of the lower portion of the lever for securing the two parts in their interlocked relation, a transverse pivot passing through the said ears and pivoting the lever to the support
- 25 and spring toggle means connecting the lower portion of the lever with the yoke to produce a snap action of the latter.
5. An electric switch including a support having spaced sides, a switch blade carrying yoke hung from the exterior of the sides of the support, a lever operating between the sides of the support and composed of an inverted approximately U-shaped lower portion provided at the top with laterally alined ears and having terminal recesses, a pin extending beneath the top of the lower portion of the lever and piercing the said lugs to secure the upper and lower portions of the lever in their interlocked relation, a transverse pivot passing through the ears and arranged above the said pin and pivoting the lever to the sides of the support and spring toggle means connecting the sides of the lower portion of the lever with the bottom of the yoke to produce a snap action of the latter.
- 30 6. An electric switch including a support, a switch blade carrying yoke pivoted to the support, a lever composed of a lower portion having spaced sides and a connecting top portion and provided thereat with terminal recesses and having transversely alined perforations located between the terminal recesses, an upper portion fitted against the top of the lower portion of the lever and provided with a transverse recess located at the said perforations, a transverse pivot passing through the perforations and arranged in a transverse recess of the upper portion of the lever and pivoting the latter to the support, a pin piercing the said lugs and passing beneath the transverse pivot and spring toggle means connecting the yoke with the lower portion of the lever.
- 35 7. An electric switch including a support, a switch blade carrying yoke pivoted to the support, a lever composed of an approximately inverted U-shaped lower portion, an upper portion fitted against the lower portion, and having terminal lugs interlocked therewith and projecting below the top of the lower portion, said upper portion consisting of a single strip of metal centrally bent to form an upwardly projecting shank means for engaging the said lugs to secure the upper and lower portions of the lever in their interlocked relation, means for pivoting the lever to the support and spring toggle means connecting the lower portion of the lever with the yoke to produce the snap action.
- 40 8. An electric switch including a support having spaced sides, a switch blade carrying yoke pivoted to the support a lever pivoted between the sides of the support and composed of a lower portion and an upper portion constructed of a single piece of metal bent centrally to form a shank and then at right angles in opposite directions to fit
- 45 120 125 130 135 140 145 150 155 160 165 170 175 180

against the top of the lower portion of the lever, the terminals of the said single piece of metal being bent downwardly forming lugs, said lugs engaging the lower portion 5 of the lever, interlocking the upper and lower portions, means for securing the upper and lower portions of the lever in their inter-

locked relation and spring toggle means connecting the lower portion of the lever with the yoke to produce a snap action of the latter.

In testimony whereof I have hereunto set my hand.

WILLIAM ILE.
